UNITED STATES PATENT OFFICE.

JOHN E. PREST, OF FALL RIVER, MASSACHUSETTS.

THREAD-GUARD AND TRAVELER-CLEANER FOR RING-SPINNING FRAMES.

SPECIFICATION forming part of Letters Patent No. 269,231, dated December 19, 1882.

Application filed July 17, 1882. (No model.)

To all whom it may concern:

Be it known that I, JOHN E. PREST, of Fall River, in the county of Bristol, of the State of Massachusetts, have invented a new and useful Improvement in Thread-Guards and Traveler-Cleaners for Ring-Spinning Frames; and I do hereby declare the same to be described in the following specification and represented in the accompanying drawings, of which—

10 Figure 1 is a front elevation, and Fig. 2 a rear view, of three of the spindles and bobbins of a ring-spinning frame, their supporting-rails, and the ring-rail, with my invention applied thereto, the nature of it being defined 15 in the claims hereinafter made. Fig. 3 is a transverse section taken between two next adjacent rings of the ring-rail, such being so as to show in side elevation one of the thread-guards and its sustaining-shank.

20 The said invention has particular reference to the thread-guards and the traveler-cleaner, and to their connection with the ring-rail. The several thread-guards are combined with the ring-rail, so as to be movable vertically there- 25 with, and also so as to be movable backward from their positions directly between the bobbins or their spindles. Furthermore, each thread-guard is constructed in the form of a wedge or a blade having a flanged back, and 30 the shank or part for supporting the blade is curved or bent or arranged so that its lower part or foot may be directly in rear of one of the two bobbins, between which the head may be extended. There is also to such shank a 35 projection to serve as a traveler-cleaner when close up to the path of revolution of one or both of the travelers of the rings, through which the said two bobbins may extend.

In the drawings, A A A denote the spindles, 40 B B B their bobbins, C and D the spindle-supporting rails, and E the ring-rail, all of which may be constructed and applied in any well-known manner.

At the back of the ring-rail there is sup- 45 ported in suitable bearings, b b, a rod or shaft, a, which is parallel to the rail and at a short distance from it. The several thread-guards F are fastened to the said shaft, it going through their several feet e, the same being so 50 that such guards shall be movable vertically with and by the ring-rail, and also be capable of being turned or moved backward from their

positions between the bobbins, in order that they (the said guards) may not be in the way of an attendant or any hinderance to him while 55 he may be doffing the bobbins.

Each guard F has its head or part d to extend between two next adjacent bobbins, formed wedge-shaped in vertical section, or as a blade made thicker or flanged at its back or 60 upper edge, in manner as shown at e, the said head being projected from a shank, f, which is curved, so that, while the head may be immediately between two next adjacent bobbins, the foot c for reception of the sustaining-shaft 65 may be directly or about so in rear of one of such bobbins, such being so that the shank may not be an obstacle to the attendant while cleaning off that part of the upper surface of the ring-rail which may be between the rings h of 70 the said two bobbins.

The shank of each guard I provide with a traveler-cleaner, i, extended from it toward one of the rings. The said traveler-cleaners are to serve, while the travelers may be running 75 around upon the races of the rings, to intercept and remove from them (the said travelers) any filaments that may have lodged on or been taken up by or caught upon them.

By having the heads of the guards flanged 80 at their backs or wedge-shaped, as shown, the threads extending from the travelers to the yarn-guides are prevented from contact with each other, so that the guards can be made to extend a less distance above the ring-rail than 85 would be requisite were the guard-heads without the flanges, the object of having the guards extend above the ring-rail as little as possible being to prevent the guards, in their upward movement, from being forced against the yarn- 90 guides or their supporting-rail and damaging or forcing upward the same. By having the guards combined with and movable by the ring-rail, they, with it, may be counterbalanced, and as it in its movement is not as liable to 95 impinge against them as it is when they are otherwise supported, no irregularity in the winding of the yarns on the bobbins—such as often result from such impingement—can take place.

100 What I claim as my invention is as follows, viz:

1. The combination, with the spindles and the ring-rail, of the thread-guard having a

supporting-shank, curved or bent as described, whereby when the guard is between two next adjacent spindles the shank at its foot will be in or about in rear of one of such spindles, as set forth.

2. The combination, with the spindles and the ring-rail, of a thread-guard, flanged at its upper part or wedge-shaped, and having a shank curved or bent as described, whereby when the guard is between two next adjacent spindles the shank at its foot will be in or about in rear of one of such spindles, as specified.

3. A thread-guard having a supporting-shank curved or bent as described, in com-

bination with a traveler-cleaner separate from the guard and extending from the said shank, all being substantially as set forth.

4. The combination, with the spindles and the ring-rail, of the thread-guard having a 20 traveler-cleaner extending from its supporting-shank, as set forth, and also having such shank curved or bent as described, whereby when the guard is between two next adjacent spindles the shank at its foot will be in or about in rear 25 of one of such spindles.

JOHN E. PREST.
